United States Patent Office

Des. 210,514
Patented Mar. 19, 1968

210,514

BOTTLE

Herbert Brammer, London, England, assignor to Charles Mackinlay & Company Limited, Edinburgh, Scotland

Filed Apr. 26, 1966, Ser. No. 2,038

Claims priority, application Great Britain Dec. 22, 1965

Term of patent 14 years

(Cl. D9—72)

FIG. 1 is a front elevational view of a bottle showing my new design;

FIG. 2 is a rear elevational view thereof;

FIG. 3 is a side elevational view thereof;

FIG. 4 is a top plan view thereof;

FIG. 5 is a bottom plan view thereof; and

FIG. 6 is a perspective view thereof on a reduced scale.

I claim:

The ornamental design for a bottle, substantially as shown.
